CLASP FOR PLASTIC CASES

Walton B. Crane, West Los Angeles, Calif., assignor to Allied Plastics Company, Los Angeles, Calif., a copartnership composed of Dwight C. Hirsh and Harry G. Long

Application January 29, 1944, Serial No. 520,213

2 Claims. (Cl. 220—60)

1

This invention relates generally to plastics, and more particularly to clasps for plastic cases and the like.

An object of the present invention is the provision of a new and improved clasp for plastic cases and the like, such as compacts, vanity cases, cigarette cases, etc. Various types of clasps have been used in the past, and have of course been highly successful in metal construction; also there have been several types of clasps designed especially for use in plastics, and these have been suitable for certain applications. However, none of these have been found entirely suitable for such an article, for instance, as a large plastic compact, where a good, strong, easily operable clasp, not likely to open accidentally, is requisite.

A further object of the present invention is the provision of a plastic compact embodying an improved clasp.

The clasp of the present invention will be best understood from the following detailed description of one present illustrative embodiment thereof, reference for this purpose being had to the accompanying drawings, in which:

Fig. 1 is a plan view of a compact embodying the clasp, the compact being shown in closed condition;

Fig. 2 is a section on line 2—2 of Fig. 1, but showing the lid of the compact in the operation of closing. The full lines show a preliminary position, and the dotted lines indicate the resilient give of the lid and clasp as closing pressure is exerted;

Fig. 3 is a view similar to Fig. 2, but showing the device closed; and

Fig. 4 is a bottom plan detail taken as indicated by arrows 4—4 in Fig. 3.

In the drawings, numeral 10 designates a compact formed of a plastic such as cellulose acetate and embodying the clasp of the invention, and this compact includes two hinged halves or parts 11 and 12, which in this instance consist of a base and a lid, respectively. The compact chosen for illustrative purposes is to be taken as representative of any plastic case or receptacle in which the improvements of the invention may be incorporated, and the invention is of course not to be taken as limited to the specific type of case here shown.

In the particular embodiment of the invention chosen for illustrative purposes the base 11 and lid 12 are both circular in outline, and both are hollowed out to form the interior compartment 13.

The cavity within the base part 11 includes a

2

circular or cylindrical chamber 14 adapted to receive a powder puff (not shown), and below is a slightly concave depression 15 adapted to receive a quantity of face powder. The concave inner surface of this depression together with the correspondingly convex bottom surface 16 of the base refine a comparatively thin convex bottom wall 17. The base 11 is formed with a peripheral and preferably tapering flange 18, having a tapering upper surface 19. Inside this flange, on the top, is an upwardly facing horizontal annular seating surface 20, and inside and raised slightly above the latter is an annular flange 21 which defines the aforementioned circular chamber 14. The cavity within the lid part 12 is defined by a seat 25 for a mirror 26, and inside said seat by a concave inside wall surface 27, which together with the correspondingly convex outside or top surface 28 define a comparatively thin convex top wall 29. Outside seat 25 is an annular downwardly facing seat 30 adapted to seat on flange 21 of base 11, and around seat 30 is a raised annular seat 31 adapted to seat on annular seat 20 of base 11.

Lid 12 has at one side an extension 35 received between a pair of hinge lugs 36, and a metal hinge pin 37 passes through the lugs 36 and the extension 35 to provide the hinge.

Diametrically opposite from hinge extension 35 is a clasp extension 40, which is in the form of an arm whose upper side extends smoothly from the convex top wall surface 28. The curvature of the top of the compact is such that this clasp arm makes an angle of approximately 13½° with horizontal. The underside of this clasp arm is adapted to engage flat against tapered surface 19 on base 11, and the taper of this surface 19 is hence also at 13½° with horizontal. Depending from the outer end of the clasp arm is a hook part or catch 42, which is receivable in a notch or recess 43 formed in the tapered flange 18. As will appear, the lateral surfaces of this notch or recess receive the lateral surfaces of the hooked end portion of the clasp arm and may thus afford a lateral positioning or guiding support for the lid as the latter is moved into closed position. The inside or bottom surface 44 of this catch 42 is preferably formed at about 15° with vertical, so that the angle between said surface 44 and the underside of the clasp arm is a few degrees, here 1½°, less than a right angle. The bottom 45 of the notch 43 is also preferably at 15° with vertical, so there is an angle of slightly less than a right angle between the bottom of the notch and the seating surface 19.

Referring more particularly to the full line position of the lid in Fig. 2, the hook part or catch is so spaced from the hinge that it normally overlaps the surface 19 by a small fraction of an inch.

To close the compact, the lid 12 and base 11 are squeezed together with the fingers. The concave wall 29 of the lid, being of plastic, and also being comparatively thin (Figs. 2 and 3 are approximately full size and the typical wall thickness may be understood from an inspection of said figures), is somewhat flexible or resilient, and gives slightly under such pressure, with the result that it and the clasp arm bend inward slightly, and this results in the lower corner of catch 42 swinging outwardly sufficiently far to pass or clear the bottom surface 45 of the notch. Thereupon catch 42 snaps into notch 43 and the parts assume the closed position of Fig. 3. The dotted lines in Fig. 2 indicate the bending action of the wall 29 and the clasp arm 40. The parts being in the closed position of Fig. 3, the inherent resilience of the plastic lid causes it to assume its initial unstressed condition, and because the angle between the underside of the clasp arm and the inside of the catch 42 is slightly less than a right angle, the parts will be resiliently locked closed. To open the compact, upward pressure is of course exerted on the clasp arm, causing the latter and the whole top wall 29 of the lid to give slightly, and in this way the hook or catch 42 is freed or cleared from the notch.

The clasp as thus described utilizes the entire upper half or lid of the compact as a spring, which must be deformed both in closing and in opening the compact. Thus there is secured a good and dependable spring action, which is sure and strong, and which nevertheless is subject to easy and conventional manipulation by the user.

The drawing and description are of course to be understood as merely illustrative of one present embodiment of the invention; and it will be evident that various changes in design, structure and arrangement may be made without departing from the spirit and scope of the invention or of the appended claims.

I claim:

1. A compact comprising a concaved base and a concaved lid hinged thereto adapted to meet in a closing plane to define a compartment, said lid embodying a slightly bendable resilient wall, mutually abutting seating surfaces on said base and lid surrounding said compartment, a peripheral flange on said base projecting outwardly beyond the periphery of said lid, a clasp arm with a hooked end portion projecting from the periphery of said lid oppositely from the hinge,

a notch in said flange adapted to receive the hooked portion of said clasp arm, a locking seat at the bottom of said notch over which said hooked portion of said clasp arm is engageable when said lid is moved to closed position, and a surface on said base flange immediately inwardly of said seat in said notch and facing toward said clasp arm, said clasp arm being so disposed that its hooked end normally slightly overlaps said last mentioned surface, but is adapted to clear said surface and engage said locking seat when said bendable resilient wall of said lid and its clasp arm are deflected inwardly.

2. A compact comprising a concaved base and a concaved lid hinged thereto adapted to meet in a closing plane to define a compartment, said lid embodying a slightly bendable resilient wall, mutually abutting seating surfaces on said base and lid surrounding said compartment, a peripheral flange on said base projecting outwardly beyond the periphery of said lid, a clasp arm with a hooked end portion projecting from the periphery of said lid oppositely from the hinge, a notch in said flange adapted to receive the hooked portion of said clasp arm, a locking seat at the bottom of said notch over which said hooked portion of said clasp arm is engageable when said lid is moved to closed position, and an outwardly and downwardly inclined surface on said base flange located immediately inwardly of said seat in said notch, said clasp arm being so disposed that its hooked end normally slightly overlaps said last mentioned surface, but is adapted to clear said surface and engage said locking seat when said bendable resilient wall of said lid and its clasp arm are deflected inwardly.
